DESIGN FOR A LENS FOR MOTOR VEHICLE LAMPS

Oliver C. Ritz-Woller, Chicago, Ill.

Application May 27, 1935, Serial No. 57,035

Term of patent 7 years

To all whom it may concern:

Be it known that I, Oliver C. Ritz-Woller, a citizen of the United States, residing at Chicago, in the county of Cook and State of Illinois, have invented a new, original, and ornamental Design for a Lens for Motor Vehicle Lamps, of which the following is a specification, reference being had to the accompanying drawing, forming part thereof.

In the drawing,—

Fig. 1 is a side elevational view of a lens embodying my new design;

Fig. 2 is a bottom plan view of the device; and
Fig. 3 is a sectional view of the device.

I claim:

The ornamental design for a lens for motor vehicle lamps substantially as shown.

OLIVER C. RITZ-WOLLER.
